DESIGN FOR A HANDKERCHIEF POCKET TOP APPLIQUÉ FOR WEARING APPAREL

Charles Emmey, New York, N. Y.

Application July 11, 1936, Serial No. 63,791

Term of patent 7 years

To all whom it may concern:

Be it known that I, Charles Emmey, a citizen of the United States, residing in the city and county of New York, State of New York, have invented a new, original, and ornamental Design for a Handkerchief Pocket Top Appliqué for Wearing Apparel, of which the following is a specification, reference being had to the accompanying drawing, forming part thereof.

The figure is a plan view of a handkerchief pocket top appliqué for wearing apparel showing my design.

Said view shows a trifolded handkerchief with a decorative cross strip. The design as shown is of no appreciable thickness.

I claim:

The ornamental design for a handkerchief pocket top appliqué for wearing apparel, substantially as shown and described.

CHARLES EMMEY.
